HATCH COVER FASTENER

William M. Dwyer, Chicago, Ill., assignor to W. H. Miner, Inc., Chicago, Ill., a corporation of Delaware

Application February 13, 1939, Serial No. 256,027

6 Claims. (Cl. 292—265)

This invention relates to improvements in hatch cover fasteners for refrigerator cars.

One object of the invention is to provide a fastener for hinged hatch covers of refrigerator cars comprising a locking lever arm swingingly supported adjacent the free edge of the cover adapted to be swung into overlying relation with respect to said cover to force the same closed and hold it in said closed position, wherein the lever arm also serves as means for supporting the cover in partly open position for ventilating purposes.

A more specific object of the invention is to provide in a mechanism as specified in the preceding paragraph cooperating means on the cover and lever arm for locking the cover to said arm to hold the former in various positions of partly open condition, together with cooperating inter-engaging means on said cover and arm for accurately supporting the cover so that it may be readily locked in any one of said partly open positions selected.

Other objects of the invention will more clearly appear from the description and claims hereinafter following.

In the drawings forming a part of this specification, Figure 1 is a plan view of a portion of the roof of a refrigerator car, showing part of the usual hatch cover, and illustrating my improvements in connection therewith. Figure 2 is a vertical sectional view, corresponding substantially to the line 2—2 of Figure 1. Figure 3 is a view similar to Figure 2, but showing the cover in partly open position and supported in said position for ventilating purposes. Figure 4 is a front edge elevational view of a portion of the lever arm for holding the cover partly open.

In said drawings, 10 indicates a portion of the roof of a refrigerator car, 11 the usual hatchway, and 12 the hatch cover. As shown, the hatchway is provided with a lining 13 which extends above the roof proper of the car. The cover 12 comprises a substantially flat main body portion 14 and a projecting plug portion 15 on the inner side thereof. The plug portion 15 is seated in the hatchway 11 and the body portion 14 of the cover overlaps the walls of the hatchway when the cover is in closed position. The cover 12 is swingingly supported in the usual manner by hinges, not shown, along one edge thereof. This hinged arrangement of the hatch cover is well known in this art as illustrated in Patent No. 2,074,464, granted March 23, 1937.

55 My improved hatch cover fastener comprises

broadly a combined supporting and locking lever arm A; a pivot bracket B; a latch C for locking the arm A to the cover; and latch means D for locking the cover to the arm to support the cover in partly open position.

The lever arm A is in the form of an elongated member having one end section 16 thereof bent at an angle to the major portion of the same, which major portion is substantially straight. The bent end section, which is indicated by 16, is pivoted to the bracket B as hereinafter pointed out. The outer end portion of said section 16 is angularly offset, as indicated at 17. The major portion of the straight section of the arm A is of substantially T-shaped cross section, comprising a flat barlike portion 18 and reinforcing flanges forming a web 19 extending along the back edge of said bar and projecting from opposite sides thereof. The web 19 extends from end to end of the arm A and at said bent portion 20 of said arm is provided with spaced side flanges 20—20 parallel to the barlike portion 18 and forming side walls on said arm. The side walls 20—20 extend along said arm to the inner end of said barlike portion 18 and are connected to 25 the latter by a transverse wall 21 formed integral therewith. Spaced from said transverse wall 21 is a second transverse wall 22, thus providing a 30 socket 23.

As shown most clearly in Figures 2 and 3, the barlike portion 18 of the arm A is provided with a plurality of locking bolt receiving openings 24—24 arranged in series lengthwise of said portion. The barlike portion 18 of the arm A is further provided with a plurality of ribs 25—25 35 on opposite sides of the same, the ribs at each side of the bar being arranged in series lengthwise thereof and each rib extending substantially transversely of said bar, that is, from the back to the front edge thereof. As shown most clearly in Figures 1 and 4, the ribs of said two series are arranged in transversely aligned pairs on opposite sides of the bar 18. Each of the ribs 25—25 is inclined with respect to a plane at right angles to the longitudinal axis of the arm A, the 45 inclination of the ribs of said series gradually increasing from the outer to the inner end of said arm so as to properly align with the projecting engaging means on the cover 12 hereinafter described. The ribs 25—25 at each side of the 50 bar 18 correspond in number to the openings 24, a rib 25 being disposed inwardly of each opening. These ribs are spaced equal distances from the openings 24—24, as clearly shown in Figures 2 and 3, to properly align the projection on the 55

cover 12, hereinbefore mentioned, with said locking openings 24-24. At each opening 24 the bar 18 is preferably increased in width to reinforce the bar at said opening, a series of rounded portions 26-26 being thus provided along the front edge of said bar. The bar is swingingly supported on the bracket B, the inner or bent end 16 of said bar being pivoted to the bracket B by a bolt 27, so that the bar may be swung toward and away 10 from the cover 12 and into overlying relation with respect to the same.

The latch plate C comprises a sliding latch bolt 28 mounted on a bracket 29 fixed to the top of the hatch cover 12. The bracket 29 comprises 15 a base portion having upstanding spaced lugs 30-30 between which the barlike portion 18 of the lever arm A is adapted to engage, the lugs being provided with aligned openings through which the bolt 28 may be projected to engage 20 through one of the openings 24 of the arm A to lock the same to the cover 12 and hold the latter in closed position. The closed position is shown in Figures 1 and 2 and as thus illustrated the locking bolt 28 is engaged through the third 25 opening from the free end of the lever arm A. Any suitable means may be provided for slidably guiding the bolt, the latter being preferably provided with a laterally enlarged slotted section 31 through the slot of which extends an upstanding 30 guide post 32 mounted on the bracket 29. As shown, the outer end of the bolt 28 is preferably hooked, as indicated at 33, to provide a convenient gripping portion for manipulating the same.

The latch means D comprises a sliding bolt 34 35 mounted on a bracket 35 secured to the cover 12 at the free edge thereof. As shown in Figures 2 and 3, the base of the bracket is in the form of an angular plate having the angularly disposed sections thereof secured respectively to the top 40 and the end edge of the cover 12. An outstanding forked lug 36 is provided on the bracket 35, the forked portion of the lug being adapted to receive the bar portion 18 of the arm A therebetween. The arms of said forked portion are 45 perforated to receive the locking bolt 34 in order to lock the cover 12 to the arm A and hold the latter in partly open position as shown in Figure 3. The bolt 34 is guided for sliding movement by an outstanding post 37 engaging in an elongated slot provided in the rear end portion of 50 said bolt. This guide means is similar to the post and slot guide means 32-31 shown in Figure 1 and operates in a similar manner, and therefore needs no further detailed description.

The lug 36 also serves as an abutment with 55 which a dog 38 pivoted on the lever arm A engages when said arm is swung on its pivot to pry the cover open. This particular mechanism, last named, and the operation thereof is old and well-known in this art, as disclosed in Patent No. 2,074,464 hereinbefore referred to.

In forcing the cover closed, the lever arm A is 60 folded over the cover and pressed downwardly in a manner described in said patent, an abutment 65 block 39 fixed within the socket 23 engaging the upper side of the cover 12 to force the same downwardly as the lever A is depressed.

To adjust the hatch cover 12 for ventilating 70 purposes, the same is lifted to approximately the height desired and the lever arm A swung in a direction toward the cover so as to engage the proper pair of transversely aligned ribs 25-25 of the arm beneath the forked lug 36 of said cover in supporting relation to said lug. The perforations 75 in the arms of the fork of the lug 36 being

thus brought into alignment with the corresponding opening 25 of the arm A, the cover is locked in said position by the sliding bolt 34.

In Figure 3 the lug 36 is shown as supported by the outermost pair of ribs 25-25 on the arm A and the locking bolt 34 engaged through the perforations of said lug and the outermost recess 24 of the series. The cover is thus held in the maximum open position in which it may be locked for ventilating purposes. As will be evident, the plurality of openings 24-24 in the arm A and the cooperating supporting ribs 25-25 which form shelves to support the lug on the cover 12, provide for adjustment of the cover within relatively wide limits for ventilating purposes, thereby meeting all possible conditions encountered in railway practice.

I have herein shown and described what I now consider the preferred manner of carrying out my invention, but the same is merely illustrative 20 and I contemplate all changes and modifications that come within the scope of the claims appended hereto.

I claim:

1. In a fastener for hinged hatch covers of 25 refrigerator cars, the combination with a lug projecting from the free edge of the cover; of an arm swingingly mounted on a fixed support and having means thereon engageable with said lug for prying the cover open, said arm having a 30 plurality of supporting ribs thereon, said ribs extending transversely of the arm and being arranged in series lengthwise of the arm, said ribs of said series being spaced apart lengthwise of said arm to accommodate said lug therebetween 35 and serving as supports for said lug to hold the cover in different adjustments of partly open position.

2. In a fastener for hinged hatch covers of 40 refrigerator cars, the combination with an upstanding perforated lug on the top of said cover spaced inwardly from the edge thereof; of a perforated lug extending from the free edge of said cover; a swinging arm pivoted to a fixed support adjacent the free edge of the cover, said arm having a series of openings arranged lengthwise 45 thereof, said arm being foldable over the cover to force said cover to closed position and hold the same in said position; a latch bolt engageable through said upstanding lug and one of the openings of said series to lock the cover in closed position; a support for said latch bolt on which the same is slidably guided in alignment with the perforation of said upstanding lug; and means engageable through said perforated lug and one 50 of said openings of said series to lock said cover in partly open position for ventilating purposes.

3. In a fastener for hinged hatch covers for 55 refrigerator cars, the combination with an outstanding lug on the free edge of said cover; of an arm pivotally mounted on a fixed support adjacent said free edge, said arm having a plurality of transverse, longitudinally spaced supporting ribs projecting from one side thereof on any one of which said lug may be supported, and 60 a latch receiving opening extending through said arm adjacent each projecting rib adapted to align with the perforation of said lug when the latter is supported by the corresponding rib; and a sliding latch bolt engageable through said perforation of the lug and the aligned opening of the arm to lock said arm to the cover in supporting relation.

4. In a fastener for hinged hatch covers for 70 refrigerator cars, the combination with an arm 75

swingly supported adjacent the free edge of the cover; of a plurality of transversely disposed, projecting ribs on one side of said arm providing supporting shelves, said shelves being arranged in series lengthwise of said arm, said arm having an opening adjacent each shelf; a lug on said cover adapted to be engaged with and supported by any one of said shelves; and latch means engageable through said lug and the opening adjacent the shelf on which said lug is supported for locking the cover to said arm.

5. In a fastener for hinged hatch covers for refrigerator cars, the combination with an up-standing supporting arm adjacent the free edge of said cover, said arm having a plurality of openings therethrough arranged in series lengthwise of said arm; of a transversely aligned pair of supporting shelves on said arm below each opening, the shelves of said pair projecting from opposite sides of said arm; a lug on the free edge of said cover engageable with any one of said pairs of supporting shelves to be supported thereon, said lug having a bolt receiving opening therethrough; and a locking bolt engageable through

the opening of said lug and the opening in said arm above the shelves on which said lug is supported for locking the cover to said support.

6. In a fastener for hinged hatch covers for refrigerator cars, the combination with an up-standing supporting arm adjacent the free edge of said cover, said arm having a plurality of bolt receiving openings therethrough arranged in series lengthwise of the arm; of a set of supporting shelves on opposite sides of said arm below each opening thereof, said shelves being arranged in transversely aligned pairs; a forked lug on the free edge of said cover adapted to embrace said arm, said forked lug being engageable with any one of said pairs of supporting shelves and resting thereon, the members of the fork of said lug having aligned bolt receiving openings; and a latch bolt engageable through said openings of the fork and the opening of said arm immediately above the pair of shelves on which the forked lug is supported for locking the cover to said arm.

WILLIAM M. DWYER.

DISCLAIMER

2,205,556.—*William M. Dwyer*, Chicago, Ill. HATCH COVER FASTENER. Patent dated June 25, 1940. Disclaimer filed September 7, 1942, by the assignee, *W. H. Miner, Inc.*

Hereby enters this disclaimer to claims 3 and 4 of said patent.
